ABSTRACT: Solid ceramic plugs are cemented into axial grooves at the periphery of a ceramic regenerator core with a cement having a high coefficient of thermal expansion. The thermal expansion of the cement exerts forces on the rim portion of the regenerator core to counteract tensile stresses in the rim portion caused by expansion of the core interior. A foam cement having low thermal expansion can be used on the inner area of the plug and high expansion cement can be used only on the outer area.

HEAT EXCHANGER FOR A GAS TURBINE ENGINE

SUMMARY OF THE INVENTION

When the ceramic regenerator core for high temperature gas turbine engines was developed, a relatively new rim-type driving system for the core also was introduced. Serious cracking problems were encountered in initial testing of the ceramic core and rimtype driving systems. Several different arrangements for assembling the driving ring gear to the core periphery to eliminate stresses have been proposed and tested, but none of the systems has been completely satisfactory in eliminating core cracking, especially when gas temperatures are increased to increase engine efficiency.

This invention resulted from the discovery that core cracking was caused by thermally induced stresses in the core itself rather than by driving stresses caused by the relationship of the driving gear to the core periphery. Careful analysis showed that the interior portion of the regenerator core reached temperatures exceeding 1,300° F. while the rim portion of the core, which was subjected to the relatively cool gases from the engine compressor, generally operated at about 450° F.

The resulting thermal expansion of the interior portion of the core produces tensile stresses in the rim portion and these tensile stresses eventually result in cracks appearing at the rim. This invention eliminates the cracks by forming a plurality of grooves in the outer surface of the rim of a regenerator and filling the grooves with a material having a high coefficient of thermal expansion. As the regenerator core warms up during engine operation, the material exerts expansion forces on the rim portion that reduce the tensile stresses in the rim below the point where cracking occurs for all anticipated operating temperatures.

Solid ceramic plugs are used in regenerator cores utilizing the rim drive techniques to transmit driving forces from the ring gear surrounding the core to the core itself. These plugs can be bonded into the core by a cement made up of high thermal expansion material. A highly useful arrangement involves bonding a portion of the outer area of the plug to the regenerator core with the high thermal expansion cement and bonding the remaining portion of the plug bond area to the core with a cement having a thermal expansion approximately equal to the thermal expansion characteristics of the core itself. In this arrangement, the low expansion cement retains the plug in place despite centrifugal, thermal, and drive loads while the high expansion material exerts the compressive forces on the rim that prevent rim cracking.

BRIEF DESCRIPTION OF THE DRAWINGS

FIG. 1 is a perspective view of a disc-shaped ceramic regenerator core having a plurality of driving plugs bonded into its outer periphery.

FIG. 2 is a perspective view of a portion of the regenerator core showing a plug bonded to the core by the two types of cements having high and low thermal expansion characteristics.

DETAILED DESCRIPTION

A disc-type ceramic regenerator core is represented in the drawings by numeral 10. Regenerator core 10 has a solid ceramic hub 12 surrounded by a gas conducting ceramic material 14. Material 14 comprises a plurality of thin ceramic walls defining a plurality of gas conducting passages that conduct gases in a substantially axial direction through the regenerator core. Porous material 14 extends completely out to the outer periphery of the regenerator core. When mounted in the engine, one face 15 of the core is exposed to hot gases leaving the engine turbine wheels and this face along with its axially adjacent parts of the core operate at a higher temperature than the remainder of the core.

A plurality of grooves 16 are spaced along the outer periphery of the regenerator core. Grooves 16 generally parallel the rotational axis of the core. Mounted in each groove 16 is a solid ceramic plug 18. Both grooves 16 and plugs 18 have

a cross section substantially corresponding to a sector of a cylinder.

Plugs 18 are bonded into grooves 16 with two types of cements 20 and 22. Cement 20 is a foam type inorganic cement having thermal expansion properties substantially equaling the thermal expansion properties of porous material 14. A typical foam cement useful in this invention can be obtained from the Dow Corning Corp. Foam cement 20 is applied to the inner sector 21 of the cylindrical surface of each plug for a short distance from the hot face 15 and to the entire bond surface for the remainder of the plug.

Cement 22 is a material having thermal expansion props exceeding thermal expansion properties of material 14. A typical high expansion cement comprises mullite in sodium silicate and can be obtained from the Carborundum Company. Cement 22 is applied to the outer sectors of each plug on both sides of inner sector 21. Plugs 18 can be attached to an annular ring gear to transmit driving forces to the regenerator core in any desired manner (See, for example, U.S. Pat. No. 3,401,741 Paluszny et al).

In a typical disc-type regenerator having a diameter of approximately 28 inches and an axial thickness of about 4 inches, plugs 18 are semicylindrical and have a radius of approximately 1 inch. Cements 20 and 22 are applied in layers that produce a thickness of about 0.1 inch after curing. Cement 22 typically is applied to at least the radially outer 0.5 inch for an axial distance of about 1—2 inches of the surfaces between the regenerator core and the plugs.

During engine operation, hot combustion gases passing through the regenerator heat the central portion of face 15 and its axially adjacent portions of the regenerator to temperatures exceeding 1,300° F. The periphery of the regenerator is subjected to the relatively cool air leaving the engine compressor and operates at about 450° F. As the temperature of cement 22 rises to its operating point, the high thermal expansion properties thereof exert compressive forces in the direction of arrows 24 the material 14 in the rim portion of the regenerator core. These compressive forces reduce the tensile stresses in the rim portion and thereby reduce the cracking tendencies of the core. Cement 20 does not expand to the same degree as cement 22 and provides strong adhesion between the core and the plug to hold the plug in place.

If desired, cement 22 can be applied to the entire axial thickness of core 10 on both sides of a sector of cement 20. In some cases, cement 22 can be used exclusively. Grooves 16 can be reduced considerably in size and filled only with a cement having the high thermal expansion properties of cement 22. The number of grooves generally depends on the expansion characteristics of the core and the cement and the anticipated operating conditions of the engine. A few empirical tests generally are sufficient to determine both the number and size of the grooves. Thin slats of a material having a high thermal expansion can be located in the grooves. Alternatively, the grooves can be shaped like scalloped slots extending for short distances into the core from hot face 15 at the core periphery and the slots filled with high expansion material.

The high expansion cement preferably has a higher coefficient of thermal expansion for temperatures ranging up to its operating temperature, usually about 450° F., and a reduced coefficient of expansion at temperatures between the operating temperature and the higher firing temperature of the two cements, which usually is about 1,000° F. A graph of the expansion characteristics of the two cements thus shows the expansion curve of the high expansion cement rising rapidly to temperatures of about 450° F. and then leveling off to approach or cross the expansion curve of the other cement. The mullite and sodium silicate cement disclosed above has these characteristics. This arrangement permits firing the core and plug assembly without inducing excessive stresses in the bonds of the plugs to the core.

Thus this invention provides a heat exchanger for a gas turbine engine that has improved physical integrity and a long service life even at high operating temperatures. Heat exchan-

gers having a rim type driving system can incorporate the invention with a minimum of expense.

I claim:

1. In a gas turbine engine, a rotary heat exchanger comprising a regenerator core made of a ceramic material, said core having a plurality of thin walls defining a plurality of gas-conducting passages, said core having a central portion of at least one face subjected to relatively high temperatures and a rim portion surrounding that central portion, said rim portion being subjected to lower temperatures, said regenerator having a plurality of grooves in the outer surface of said rim portion, and a second material having a high coefficient of thermal expansion relative to the ceramic material of the core in said grooves, said second material exerting expansion forces on the rim portion to reduce tensile stresses in said rim portion.

2. The engine of claim 1 comprising a solid ceramic plug located in each of said grooves, said plugs being bonded in place by a cement made up of said high thermal expansion material.

3. The engine of claim 2 in which the regenerator core is disc-shaped and the gas-conducting passages run substantially axially through said disc, said grooves running axially along the outer periphery of the core and having a cross section corresponding to a sector of a cylinder, said plugs having a cross section substantially corresponding to the cross section of said grooves, the inner area of the surface of each plug being bonded to the core with a cement having a thermal expansion approximately equal to the thermal expansion of the core, and the outer area being bonded to the core by said high thermal expansion cement.

4. The engine of claim 3 in which the high expansion cement is used only in said outer areas of the surface between the plug and the core at the hot face of the core and for a short axial distance from said hot face of the core.

5. The engine of claim 4 in which the high expansion cement has a coefficient of expansion greater than the core at temperatures up to its normal operating temperature and a reduced coefficient of expansion at higher temperatures.
